W. PRINCE

SELF SUPPORTING LADDER

Filed Feb. 18, 1924

UNITED STATES PATENT OFFICE.

WILLIS PRINCE, OF MONMOUTH, MAINE.

SELF-SUPPORTING LADDER.

Application filed February 18, 1924. Serial No. 693,595.

To all whom it may concern:

Be it known that I, WILLIS PRINCE, a citizen of the United States, residing at Monmouth, in the county of Kennebec and State 5 of Maine, have invented certain new and useful Improvements in Self-Supporting Ladders; and I do declare the following to be a full, clear, and exact description of the invention, such as will enable others skilled 10 in the art to which it appertains to make and use the same.

My invention aims to provide a very convenient self-supporting ladder which may be easily folded when not in use, yet will be exceptionally rigid when extended, the device 15 being primarily intended for use by fruit-pickers.

Another object of the invention is to make novel provision to cause the ladder to stand 20 evenly upon the ground regardless of irregularities in the latter.

With the foregoing in view, the invention resides in the novel subject matter herein-after described and claimed, the description 25 being supplemented by the accompanying drawing.

Figure 1 is a perspective view of a ladder constructed in accordance with my invention.

30 Figures 2 and 3 are vertical sectional views as indicated by lines 2-2 and 3-3 of Figure 1.

Figure 4 is a detail perspective view showing the ladder bracing structure in a different position from that disclosed in Fig. 1.

In the drawing above briefly described, the numerals 1 designate a pair of stiles which carry rungs 2 of any desired form, the upper ends of said stiles being preferably secured 40 against a spacing block 3, while I prefer to provide their lower ends with a pair of spikes 4 adapted to penetrate the ground to prevent slippage.

45 A pair of arms 5 are located near the upper ends of the stiles 1 and are pivoted at 6 to said stiles, the free ends of said arms having alined bearings 7. These bearings receive trunnions 8 on the upper end of a legged brace structure 9, upon whose upper 50 end, the lower edges of the stiles 1 are intended to rest. The trunnions 8 are provided with pins 10 or other suitable stops, adapted to abut the outer sides of the bearings 7, and the outer sides of the stiles 1 are provided with wedges 11 to engage the inner sides of said bearings, thus wedging

the latter tightly outward against the stops 10, when the ladder is set up in condition for use. By this construction, the bracing structure 9 and the main ladder structure 60 may be pivotally adjusted as occasion may require but will be effectively held in any adjusted position. In some instances, if desired, the arms 5 may be swung downwardly as indicated in Fig. 4, instead of upwardly 65 as shown in Figs. 1 and 3, as the ladder may be more conveniently used in this condition, in certain cases.

The brace structure 9 preferably comprises a pair of legs 12 having their upper 70 end portions secured against opposite sides of a spacing block 13, and to form the trunnions 8, I preferably make use of a horizontally elongated cylindrical member 14 whose lower side is notched as at 15 to receive the upper 75 extremities of said legs 12 and block 13, any suitable means, such as a bolt 16 being provided for securing the member 14 to the block 13. By employing this construction, the end walls of the notch 15 effectively hold the legs 12 against the block 13, so that they cannot separate to any extent from the latter.

I have shown a pair of spacing bars 17 and 18 extending between the legs 12, and 80 upper and lower rods 19 and 20 also extending between said legs, the rod 20 being near the lower ends of the legs and the bar 18 being slightly above this rod. This last named bar is preferably enlarged at its 85 center and formed with an elongated slot 21 which opens through its upper and lower edges. An extension 22 is provided to contact with the inner side of either of the legs 12, said extension being formed with a vertical slot 23 receiving the rod 20. Suitable means, such as T-headed bolts 25, having thumb-nuts 26, may be provided to secure the extension 22 against the inner side of either of the legs 12. To effectively brace 90 the extension 22, regardless of its position, I provide a brace arm 27 which is pivoted at 28 to the upper end of said extension. This brace arm inclines from the pivot 28 and passes through the slot 21, the upper 95 end of said arm being formed with a longitudinal slot 29. A clamping and pivot bolt 30 passes through the cross bar 18 and through the slot 29 and may well be provided with a thumb-nut 31. When this nut is tightened, the arm 27 is held so as to effectively brace the extension 22. By 100 105 110

loosening the nuts 31 and 26 however, it will be seen that vertical adjustment of the extension is permitted. Also, by turning one of the bolts 25 so that its head will slip through the slot 23, the extension may be moved into engagement with the opposite leg 12 whenever desirable.

Excellent results may be obtained from the details disclosed and they may therefore be followed if desired, but within the scope of the invention as claimed, numerous minor changes may be made.

I claim:

1. A ladder comprising rung-supporting stiles, a pair of vertically movable arms pivoted to the outer sides of said stiles near their upper ends, the free ends of said arms having alined bearings, a legged brace structure upon whose upper end the lower edges of said stiles may rest, said brace structure having oppositely extending trunnions received in the aforesaid bearings and provided with stops to abut the outer sides of said bearings, and wedge surfaces carried by said stiles to wedge said bearings tightly outward against said stops.

2. A ladder comprising rung-supporting stiles, a pair of vertically movable arms pivoted to the outer sides of said stiles near their upper ends, the free ends of said arms having alined bearings, a pair of brace legs for said stiles, a block between the upper ends of said legs to which they are secured, a horizontally elongated stile supporting member extending across the upper edge of said block and the upper ends of said legs and having trunnion-forming ends projecting laterally from said legs and received in said bearings, the lower side of said mem-

ber having a notch receiving said block and leg ends, stops on said trunnion-forming ends of said member adapted to abut the outer sides of said bearings, and wedge surfaces carried by said stiles and adapted to force said bearings tightly outward against 45 said stops.

3. A ladder comprising spaced legs, a cross bar connecting said legs above their lower ends, an extension movable from one of said legs to the other and adapted to 50 contact with the inner side of either, means for securing said extension to either leg for vertical adjustment, a brace arm pivoted to the upper end of said extension and adapted to incline in either of two directions therefrom, said arm crossing said cross bar, and means pivotally and adjustably connecting said arm to substantially the center of said cross bar.

4. A ladder comprising spaced legs, a 55 cross bar connecting said legs above their lower ends and having a central slot opening through its upper and lower edges, an extension movable from one of said legs to the other and adapted to contact with the inner side of either, said extension having a vertical slot, fastening means adapted for passage through the last named slot to secure the extension adjustably to either of said legs, a brace arm pivoted to the upper 60 end of said extension and passing through the slot of the aforesaid cross bar, said arm having a slot, and a clamping and pivot bolt passing through said cross bar and 75 said slot of the arm.

In testimony whereof I have hereunto affixed my signature.

WILLIS PRINCE.
